UNITED STATES PATENT OFFICE.

COWAN D. WILSON, OF BIG STONE GAP, VIRGINIA.

WRENCH.

1,155,857.

Specification of Letters Patent.

Patented Oct. 5, 1915.

Application filed March 17, 1914. Serial No. 825,323.

To all whom it may concern:

Be it known that I, COWAN D. WILSON, a citizen of the United States, residing at Big Stone Gap, in the county of Wise and State of Virginia, have invented new and useful Improvements in Wrenches, of which the following is a specification.

The present invention relates to improvements in nut wrenches which are operated by a turning handle, and it has for its object to provide a simply constructed and operated wrench which is durable and easy to handle, and one which may be quickly and easily adjusted to clamping or unclamping position with relation to an object to be operated upon by the wrench.

Another object of the invention is to embody in a wrench a strong and durable construction which can be manufactured cheaply and wherein all of the parts shall be removable and changeable.

A still further object of the invention is to provide a stationary jaw with a rod or tubular shank, to arrange a slidable jaw upon the shank and retain the same thereon against rotary movement, and to provide a handle which shall comprise a hollow tubular member that has a swivel connection with the movable jaw, and further to provide the handle with a compressible lubricant soaked pad which, when contacted between the end of the handle and the end of the shank serves to lubricate the same and so materially assist in the connection and accurate operation of the handle upon the shank.

Other objects and advantages will appear as the nature of the invention is more fully understood.

40 The improvement resides in the construction, combination and arrangement of parts set forth in the following specification and falling within the scope of the appended claims.

45 In the drawing: Figure 1 is a side elevation of a wrench constructed in accordance with the present invention, Fig. 2 is a similar view, the tubular handle being shown in longitudinal section, Fig. 3 is a transverse section on the line 3—3 of Fig. 2, Fig. 4 is a similar section on the line 4—4 of Fig. 2, Fig. 5 is a perspective view of the movable jaw, and Fig. 6 is a view looking toward the end of the shank and stationary jaw.

55 Referring now to the drawing in detail, 1 designates the fixed jaw which may be in

the form here shown, or of any other suitable form. The jaw 1 is provided with a round shank 2 which may be hollow or solid. The shank 2 is formed with a threaded extension 3 which preferably has its outer end closed, when the shank is tubular. The rounded shank 3, upon what I will term its lower face, is provided centrally with a longitudinally arranged depression 4, the upper wall of which being disposed flush with the threads of the end 3, and the side walls of the depression 4 are preferably beveled or inclined toward each other at the top wall thereof.

70 The movable jaw is indicated by the numeral 5 and the said jaw is formed with a round opening 6 whereby the jaw proper is arranged upon the shank 2. The jaw 5 has connected therewith, through the medium of a web 7, a collar 8, the said collar having its opening or bore agreeing in size with the rounded shank 2, and the web 7 has, what I will term, its underface arched from its connection with the inner face of the jaw 5 to the lower face of the collar 8, and the portion of the web arranged adjacent the shank 2 is rounded to receive the said shank. The web 7 between the portion of the jaw 5 provided with the opening 6, and which for convenience may be termed a collar, and the second collar 8 is centrally provided with a longitudinally extending tongue 9, the said tongue preferably having beveled or inclined sides to agree with the inclined side walls provided by the depression 4. It will be noted that an arrangement as just set forth, the movable jaw 5 may be inserted over the threaded end 3 of the shank 2 until its tongue 9 is brought into engagement between the walls of the depression 4, so that the arrangement of the slidable jaw of the wrench does not interfere with the threads 3, and also whereby the slidable jaw may be readily removed when worn or for other purposes.

75 The outer face of the collar 8 at the lower portion thereof or at its connection with the web 7 is formed with an upturned lip 10 which is adapted to have a swiveled engagement with an annular bead or rib 11 formed upon the open mouth of the operating handle 12. This operating handle has its bore of two dimensions, which may be indicated by the numerals 13 and 14 respectively, the portion 13 being of a size to snugly receive the non-threaded portion of the shank 2, the

portion 14 being threaded and having its threads co-act with the threads 3 at the reduced end of the shank. The hollow operating handle 12 has arranged therein and at its outer and closed end, a lubricant pad 15. This pad is soaked with oil before being inserted within the hollow handle 12, and the bore of the handle is of a sufficient length to permit of the end of the threaded portion 10 of the shank compressing the pad when the jaw 5 is arranged upon or near the jaw 1, thus expressing the oil from the pad to cause the same to be delivered around the threads of both the shank and handle as well as to be directed through the bore 13 of the handle to within the depression 4, and so lubricate the walls of the said depression to permit of the tongue 9 sliding freely in a longitudinal direction upon the shank 2. The lubricant is also delivered to within the lip 10 and the bores of the collars 8 and 6. When all of the lubricant has been expressed from the pad, the handle 12 may be readily removed by unscrewing the same, and a lubricant may be delivered from the open mouth or end of the handle to the pad or if desired, the pad may be removed and again soaked in oil.

In a number of instances it has been found desirable that the lubricant be delivered only to the threads of the shank and handle, and in such instances, a dam in the shape of a washer may be arranged around the shoulders provided between the two bores of the handle and that portion provided between the rounded and threaded portion of the shank, or furthermore, the pit between the rounded portion of the shank and the non-threaded portion of the handle may be sufficient to prevent the lubricant passing beyond the shoulder between the threaded and non-threaded portions of the shank.

Having thus described the invention, what I claim is:

1. The herein described construction of

Copies of this patent may be obtained for five cents each, by addressing the "Commissioner of Patents, Washington, D. C."

wrenches including a fixed jaw, a cross sectionally round shank formed with and extending from the shank, the said shank having its outer end threaded and the non-threaded portion of said shank being provided with a longitudinally arranged depression, a movable jaw for the shank including a pair of spaced collars connected by a web, and the said web between the said collars being formed with a longitudinally extending tongue which is received within the depression in the shank of the stationary jaw, and a hollow handle member threaded upon the end of the shank and co-acting with the movable jaw to slide the said movable jaw upon the said shank when the said handle is rotated.

2. A wrench constructed as herein described including a jaw having a cross sectionally rounded shank provided with a reduced threaded extension, a slidable jaw, said slidable jaw including spaced collars connected by a web, said collars having round openings to receive the rounded shank of the stationary jaw, the web being formed with a longitudinally extending tongue between the said collars which is received in the depression in the said shank, the outer collar being formed with a lip, a hollow operating handle having a bore of two dimensions, the smaller of which being threaded to engage with the threaded end of the shank, a compressible element between the end of the bore and the end of the threaded shank, and the open end of the said handle being formed with an annular bead which is adapted to co-engage with the lip of the mentioned outer collar of the movable jaw.

In testimony whereof I affix my signature in presence of two witnesses.

COWAN D. WILSON.
